UNITED STATES PATENT OFFICE.

JENS N. MORTENSEN, OF BROOKLYN, NEW YORK, ASSIGNOR, BY MESNE ASSIGNMENTS, TO PEERLESS VENDING COMPANY, INC., OF NEW YORK, N. Y., A CORPORATION OF NEW YORK.

COIN-CONTROLLED VENDING MACHINE.

Application filed July 3, 1923. Serial No. 643,226.

To all whom it may concern:

Be it known that I, JENS N. MORTENSEN, a citizen of the United States, and a resident of Brooklyn, in the county of Kings and 5 State of New York, have invented certain new and useful Improvements in Coin-Controlled Vending Machines, of which the following is a specification.

The invention relates to improvements 10 in coin-controlled vending machines adapted to stand upon a counter or shelf and be utilized for the sale of chewing gum or other goods prepared in small packages and arranged in columns within the machine. 15 One purpose of the invention is to produce a comparatively small good-appearing machine having a transparent casing through which the merchandise may be observed and which although small in size is of large capacity so as to not require replenishing at 20 too frequent intervals. Another purpose of the invention is to provide a machine of the character referred to, formed of durable parts and capable of ready operation on the 25 introduction into the machine of a predetermined coin through an exposed slot formed in the base frame of the machine. Another purpose of the invention is to provide a machine which will, with 30 certainty, when operated, deliver the sold pieces of goods to the purchaser.

In carrying out my invention I provide a hollow metallic base within which the major portion of the operative mechanism is 35 contained, and upon this base I mount a vertical rotary frame having a circular series of vertical trays for the pieces of chewing gum or other merchandise sold, and this rotary frame is enclosed by a cylindrical 40 glass casing which is secured to the base frame by a central rod extending through the glass casing, said rotary frame and said base frame. The special features of the invention and the construction and operation 45 of the several mechanical parts comprising the same, will be understood from the detailed description hereinafter presented, reference being had to the accompanying drawings, in which:

50 Fig. 1 is a side elevation, partly broken away and partly in section, of a coin-controlled vending machine constructed in accordance with and embodying the invention;

Fig. 2 is a vertical section through the same, taken on the dotted line 2-2 of Fig. 3; 55

Fig. 3 is a horizontal section through the same, taken on the dotted line 3-3 of Fig. 1;

Fig. 4 is a horizontal section through the same, taken on the dotted line 4-4 of Fig. 2;

Fig. 5 is a horizontal section through the 60 same, taken on the dotted line 5-5 of Fig. 2;

Fig. 6 is a view substantially corresponding with Fig. 5, but illustrating the machine as having been started in operation, the operating lever having been moved from the initial normal position in which it is shown in Fig. 5 to that in which it is shown in Fig. 6;

Fig. 7 is a view corresponding substantially with Figs. 5 and 6, but illustrating the 70 mechanism as having been operated by the full throw of the operating lever from the position shown in Fig. 5 to that shown in Fig. 7;

Fig. 8 is an inverted plan view of the bottom of the machine, with the bottom plate thereof removed to expose the mechanism contained in the hollow base frame of the machine and with the parts shown in their normal position illustrated in Fig. 5; 75 80

Fig. 9 is a vertical section through a portion of the machine, taken on the dotted line 9-9 of Fig. 3 and being on a larger scale than Fig. 3;

Fig. 10 is a vertical section through a 85 portion of the machine, taken on the dotted line 10-10 of Fig. 3;

Fig. 11 is a vertical section through a portion of the machine, taken on the dotted line 11-11 of Fig. 3 and showing a coin as 90 having been introduced into the machine, such coin being also illustrated in Fig. 5;

Fig. 12 is a sectional view illustrating in detail the means for securing the transparent casing in position upon the base 95 frame and Fig. 13 is a vertical section through a fragmentary portion of the machine, taken on the dotted line 13-13 of Fig. 5.

In the drawings, 15 designates a hollow 100 cylindrical base frame or stand and 16 a hollow cylindrical transparent casing mounted upon said base frame and firmly secured in position thereupon by means of a central rod 17 having a polygonal head 18 105 (Fig. 2) located in a polygonal aperture in

the bottom plate 19 of said base 15, said head 18 serving to prevent the rotation of the rod 17. The lower end of the rod 17 has a head 20 engaging the bottom 19 of the base casing and aiding in securing said bottom firmly, though detachably, in position. The base frame 15 has cylindrical vertical walls and is formed with a top 21 on which the transparent casing 16 rests and 10 with a surrounding flange 14 to position said casing on said top, and said top 21 is formed with a central opening 22, whose purpose will be hereinafter explained, and also with a slot 23 for the pieces of chewing gum or 15 the like 24 (Fig. 4), as the respective columns of the merchandise are successfully brought over said opening 23. The base 15 is formed at one side with a coin entrance slot 25, which is vertical, and with an elongated horizontal slot 26 out through which the operating handle or rod 27 extends in convenient position to be moved from one end of the slot (Fig. 5) to the other end thereof (Fig. 7) and back to its first position shown in Figs. 1 and 5. The operating handle 27 will be manually moved or swung from its position shown in Fig. 1 to that illustrated in Fig. 7, and thereupon upon the release of said handle 27, the handle is 20 turned to its initial position by means of the spring 28 which is placed under tension on the movement of said handle to the position shown in Fig. 7. The base frame 15 is also formed with an exit opening 29 to 25 which the sold pieces of chewing gum automatically descend, a chute 30 being provided within the chamber of the base 15 to receive the sold pieces of merchandise and direct them downwardly to the discharge opening 29. The chute 30 will ordinarily 30 be formed of tin and is of box-formation, as shown in Figs. 2, 8, 9 and 10, said box-formation being represented in rear perspective in Figs. 2 and 10 in bottom elevation in Fig. 8 and in section in Fig. 9. The sides of the chute 30 are flanged outwardly at their outer edges, as at 31, and secured to the base frame by means of screws 32. The chute 30 is 35 stationary and rigid with the base frame 15. The glass casing 16 is in the general shape of an inverted jar and rests upon the top plate 21 of the base casting 15. Within the transparent casing 16 is confined a rotary frame 33 for holding the pieces of chewing gum or the like 24, and this rotary frame 33 is formed of tin sections whose outline is 40 more clearly represented in Fig. 3. The tin sections are arranged in circular disposition and secured at their upper ends to a ring or collar 34 by means of screws 35, and at 45 their lower ends to a ring or collar 36 by means of screws 37. The tin sections constituting the rotary frame 33 form compartments 38 for the stacks of chewing gum 24, and in the present instance there are eight

of the vertical compartments 38 adapted to contain eight vertical columns or stacks of the chewing gum. Each section of the rotary frame 33 comprises four integral members which, in Fig. 3, I number 39, 40, 41 and 42, 70 respectively. When the frame is made up of the sections each comprising the parts 39, 40, 41 and 42, the compartments 38 may stand substantially radial of the rotary frame and each of the sections may be stamped up out of sheet metal. The outer edge of the member 39 of each of the sections closely engages the adjacent outer edge of the member 42 of the next adjacent section, and the outer edge of the member 42 of each section closely 75 engages the outer edge of the member 39 of a preceding section, as illustrated at the right hand side of Fig. 3. The several sections comprising the rotary frame 33 may be readily and cheaply made and assembled, 80 and in addition they may be secured at their inner ends or members 41 to the upper and lower rings or collars 34, 36.

Upon the stacks of chewing gum 24 is loosely applied a weight 43 which is in the 85 form of a ring and has inwardly extending arms 44 to enter the compartments 38 and rest upon the upper ends of the stacks of chewing gum 24.

It is desirable that the weight 43 may 90 slide downwardly with the diminishing stacks of chewing gum 24, as the chewing gum is sold, and also desirable that the weight 43 shall not tilt upwardly from the chewing gum in the event that the machine 100 should be turned upon itself, and therefore in the members 41 of substantially opposite compartments 38 I form a vertical series of ratchet teeth 45 and provide the weight 43 with locking pins 46 which are spring-pressed against the teeth 45 and are beveled downwardly and outwardly at their inner ends to slide downwardly over the teeth 45, but become locked against upward movement by engagement with said teeth. The 105 teeth 45 are pressed out of the tin of the tray sections, and the pins 46 are mounted in horizontal openings in the weight 43 and have upwardly extending exposed outer ends or finger-holds 47 by means of which 110 the locking pins may be pressed outwardly from the ratchet teeth 45 and permit the weight 43 to be slid upwardly on the tray sections or be removed entirely therefrom. The ratchet teeth 45 incline downwardly 115 and outwardly, and the inner ends of the locking pins 46 have a like inclination, as shown in Fig. 2.

The lower collar 36 is formed with a lower hub section 48 which fits within the hole 22 120 formed in the top-plate 21 of the base-frame 15, as shown in Figs. 2 and 4, and this hub 48 serves as means for centering the rotary frame 33 within the machine. The hub 48 is less in diameter than the upper por- 125

tions of the collar 36, and hence an annular shoulder 49 is formed to seat upon the top 21 of the base frame 15 along the edges of the opening 22 therein, and by means 5 of said shoulder 49 the weight of the rotary frame 33 is supported upon the said top plate 21.

The top of the transparent casing 16 is formed with an opening 50 and within this 10 opening is suspended a sleeve 51 which is integral with a disk 52 supported upon the top of the casing 16, a packing 53 being placed below the disk 52 to cushion the pressure of said disk on the glass casing. The 15 sleeve 51 is open at its upper end and said sleeve receives the upper threaded end 54 of the rod 17, as shown in Fig. 12, said upper end of the rod 17 also having a plain stem 55 extending upwardly from its threaded 20 portion 54. The rod 17 is secured at its upper end by means of a threaded sleeve 56 which is screwed downwardly upon the threaded portion 54 of said rod 17, said sleeve 56 then entering the sleeve 51 and 25 finally becoming concealed therein, as shown in Fig. 2. The threaded sleeve 56 may be applied upon the upper threaded portion of the rod 17 by any convenient means, but I 30 preferably use for that purpose a key 57 having a hollow threaded lower end 58 adapted to enter the bore of the sleeve 56. The thread on the key 57 is left-handed and the bore of the sleeve 56 has reversely threaded sections, one to be engaged by the 35 thread on the key and the other to engage the threaded end 54 on the rod 17, and hence when the thread 58 is screwed into the sleeve 56 and by the force of the key 57 the sleeve 56 is screwed down against the bottom of 40 the sleeve 51 which becomes an arresting point, the continued motion of the key 57 operates to unscrew the key from the sleeve 56, leaving said sleeve within and against the bottom of the sleeve 51, thereby locking 45 the upper end of the rod 17 in position and securing the transparent casing 16 upon the base frame 15, the lower end of said rod having been secured against rotation within the bottom 19 of the base casing 15 50 by means of the polygonal head 18 and having been given a firm bearing against said bottom 19 by means of the head 20. The bottom 19 seats against an annular shoulder 60 formed within the lower end of the base frame 15.

Upon the rod 17 at some intermediate point I provide an adjustable stop-collar 59 which is made use of as means for preventing the complete detachment of the rotary frame 33 from the machine at such times as the sleeve 56 may be detached from the upper end of the rod 17 and the casing 16 lifted off from the base 15. When the transparent casing 16 is removed from the machine, the rotary frame 33 may be slid up-

wardly on the rod 17 for any purpose that may require such action and at such time the base of the collar 36 will strike against the stop collar 59 and arrest the frame 33 against further upward movement.

The key 57 is also made use of for removing the sleeve 56 from the upper end of the rod 17, this being accomplished by screwing the lower end of the key into the upper end of the sleeve 56 and then rotating the key for causing the sleeve 56 to ride upwardly on and from the threaded portion 54 of the rod 17.

I have described all of the features of the machine located above the top plate 21 of the base frame 15, and I will now describe the mechanical features confined within the chamber of said base frame.

Below the top plate 21 of the base 15 and close against the under surface of said top plate and against the lower surface of the hub 48, is mounted to rotate on the rod 17 with the rotary goods-holding frame 33, a plate 61 of the outline more clearly illustrated in Figs. 5, 6 and 7, this plate 61 being 85 of general disk outline and fastened to the hub 48 by means of screws 62. The outline of the plate 61 also conforms substantially to the outline in cross-section of the rotary frame 33, and the plate 61 is recessed inwardly, as at 63, to conform to the vertical compartments 38 in the frame 33 and also to conform to, as they pass in succession under, the opening 23 in the top-plate 21. The recesses 63 in the plate 61 are in the outline 90 of the pieces of chewing gum 24, and during the rotation of the goods-holding frame 33 and plate 61, the recesses 63 are successively carried below the opening 23 in the top plate 21 and receive a piece of gum 100 therefrom. The plate 61 is of the thickness of one piece of gum 24 and the top plate 21 at the opening 23 therein is of the thickness of one piece of gum, and hence in the normal position of the parts of the machine, the two lower pieces of gum of a stack or column thereof will be below the upper surface of the top plate 21, one of said pieces being in an opening 63 of the plate 61 and the other piece being in the opening 23 of the top plate 21, as shown in Figs. 2 and 10. The pieces of gum confined in the opening 23 of the top plate 21 and the recess 63 below said opening, in the plate 61, are supported upon a segmental plate 64 whose outline in bottom elevation is shown in Fig. 8 and whose outline in top view is more clearly illustrated in Figs. 6 and 7. The plate 64 defines something less than a half-circle and is mounted to oscillate upon the vertical rod 17 independently of the plate 61, which rotates with the frame 33. The plate 64 has a depending hub 65 (Fig. 2) and is supported thereat on a coiled spring 66 which is interposed upon the rod 17 between the bottom of the base 115 120 125 130

15 and a washer 67 engaging and affording a bearing for the lower end of the hub 65. The plate 64 is thus spring-pressed against the lower surface of the plate 61 and has a 5 close frictional engagement therewith. The plate 64 has along its outer edge a depending flange 98 which normally closes the slot 26 in the base 15, and to the plate 64 is fastened the handle 27 which projects out 10 through the slot 26 and by means of which said plate 64 may be moved from its initial position shown in Fig. 5 to its extreme other position shown in Fig. 7. The plate 64 is formed with an elongated opening 68 which 15 conforms to the opening 23 in the top plate 21 and the individual recesses 63 of the plate 64. The opening 68 in the plate 64 is normally not in vertical alignment with the aforesaid openings 23, 63, and hence said 20 plate 64 may support the stack of confections at said openings 23, 63 in the manner shown in Figs. 2 and 10. The plate 64 is formed with a vertical receiver 69 for a coin 25 introduced through the coin entrance slot 25 formed in the base 15, said receiver 69 being normally in line with said slot 25 so that a coin may be pushed through the slot and directly into said receiver, which 30 is open at its outer end and at its upper and lower ends and closed at its inner ends. A coin 70 pushed into the receiver 69 will 35 rest upon a segmental tramway plate 71 which is of sheet metal and secured by screws to the side wall of the base 15, as shown in Figs. 8 and 11, and the coin will remain supported on the tramway 71 until, by means of the lever or handle 27, the plate 64 is moved from its initial position, shown 40 in Fig. 1, along the slot 26 until the coin is carried beyond the far end of the tramway plate 71.

I utilize the coin 70 as means for rotating the plate 61 and rotary frame 33, said coin when introduced into the coin receiver 69 and standing on edge on the tramway plate 71, projecting upwardly within the recess 63 of the plate 61 above the coin, as shown in Figs. 5 and 11. When the coin is in the 45 position indicated in Fig. 11 with its upper edge within one of the recesses 63 of the plate 61, and the handle 27 is started in motion from its position shown in Fig. 5, the coin will on a limited movement of the plate 64 be carried against the side edge 50 of the recess 63 into which it projected, as shown in Fig. 6, and thereupon upon the continued movement of the handle 27 said coin will act as a dog pressing against the edge of said recess to rotate the plate 61 and frame 33 until the handle 27 has reached the limit of its movement toward the left, as shown in Fig. 7, the coin thus rotating the plate 61 and frame 33 to the extent of 55 the movement of the handle 27 from the position shown in Fig. 6 to that shown in 60

Fig. 7. When the handle 27 has reached its position shown in Fig. 7, the proper movement will have been given to the plate 61 and rotary frame 33 and said plate and frame will thereupon come to rest, and the 70 hand of the operator will be released from the handle 27, during the movement of the plate 64 and handle 27 from their initial position shown in Fig. 5 to that position shown in Fig. 7, the spring 28 hereinbefore referred to is placed under increased tension, and when the hand of the operator is released from the handle 27, said spring 75 will retract said plate 64 from its position shown in Fig. 7 to that shown in Figs. 5 80 and 8, thus restoring the plate 64 to its initial position without disturbing the then position of the plate 61 and frame 33. When the handle 27 is released, the pressure 85 of the coin 70 against the edge of the recess 63 becomes released and the coin falls downwardly into the chamber of the base 15. During the movement of the plate 64 from its position shown in Fig. 5 to that shown in Fig. 7, the frame 33 during its period 90 of rotation moves the stack of chewing gum from above the aligned opening 23 in the top plate 21 and the recess 63 below it of the plate 61, along the upper surface of the top plate 21, leaving the two bottom 95 pieces of the stack in the opening 23 and recess 63 where they are seen in Figs. 2 and 10, and during this same movement of the plate 64, the frame 33 carries the succeeding stack of chewing gum to position 100 above the opening 23 in the top plate.

In the normal position of the oscillatory plate 64, the opening 68 therein is directly over the chute 30, this being the condition represented in Fig. 5 in which the chute 105 30 is indicated by the dotted lines below said opening 68. It is to be noted that the opening 68 is at this time beyond the column of chewing gum whose two lower 110 pieces are in the openings 23, 63, respectively, as shown in Figs. 2 and 10. When the handle 27 is turned toward the left from the position shown in Fig. 5, the plate 64 carries the opening 68 beyond the chute 30 and around to the position in which said opening is shown in Fig. 7, and during this 115 same movement of the arm 27, the rotation of the plate 61 carries the lower piece of confection held within its recess 63, shown in Fig. 10, toward the left and to the position shown in Fig. 7, said piece of confection then being directly over the chute 30 and supported upon the plate 64. The movement of the plate 61 which carries the lower piece of gum to the position over the chute 30, also carried the succeeding recess 63 of the plate to the position previously occupied by said lower piece of gum and also, by the rotation of the frame 33, 120 carried the succeeding stack of pieces 24 to 125 130

the position occupied by that shown in Fig. 10. On this operation when the bottom piece of gum was carried to the left from the position shown in Fig. 10 to the position 5 above the chute 30 shown in Fig. 7, the piece of gum immediately over said bottom piece, or the piece held in the opening 23, became supported upon the moving plate 61 until the succeeding recess 63 of said 10 plate reached said piece of gum, and at that time said piece of gum became unsupported and fell from the opening 23 into the recess 63 of the plate 61 then positioned to receive said piece, and the succeeding 15 stack of gum having at the same time reached a position over the opening 23, the bottom piece of the stack fell into said opening 23 and upon the piece of gum which just previously fell from said opening into 20 the recess 63 of the plate 61, thus restoring the condition shown in Fig. 10 at the end of each movement of the handle 27 from its position shown in Fig. 5 to that shown 25 in Fig. 7, the one piece of goods carried around by the plate 61 to a position above the chute 30 still remaining upon the oscillatory plate 64. Upon the release of the hand of the operator from the handle 27, the spring 28 will restore said handle and 30 the plate 64 to their initial position, and when the plate 64 reaches its initial condition, the opening 68 therein is directly over the chute 30 and below the sold piece of gum, which then falls through the opening 35 68 and into the chute 30 and passes to the discharge opening 29. The sold piece of gum is not delivered during the active movement of the handle 27 from its position shown in Fig. 5 to that shown in Fig. 7, 40 but on the return movement of said handle and of the plate 64 to their initial position under the influence of the spring 28.

Within the base 15 is pivotally secured an arm 80 carrying a dog 81 which is normally held within one of the recesses 63 of the plate 64 by means of a leaf-spring 82, as shown in Fig. 7. When the dog 81 is in position in the recess 63 it will prevent the rotation of the plate 61, and at that time the oscillatory plate 64 may be moved freely, not having 50 positive connection with the plate 61. When a coin is inserted through the coin-slot 25 and the plate 64 is moved by the arm 27, a cam bar 83 rigid with said plate 64 will move 55 against the dog 81 to turn the same outwardly from the recess 63 of the plate 61 and then as the rotary plate 61 starts in motion under the force of the coin acting against it, the cam bar will pass from the dog 81 and said 60 dog will become flexed against the periphery of the plate 61 advancing toward it in rear of the recess the dog had just occupied and which has advanced in a direction from the dog (Fig. 6). Upon the plate 61 completing 65 its predetermined movement the dog 81 will enter the succeeding recess 63 then brought opposite to the dog (Fig. 7) and again lock the plate 61 against movement with the plate 64 except after said plate 64 has returned to its initial position and another coin has been 70 inserted into the machine. When the plate 64 is moved without a coin having been introduced into the machine, the cam-bar 83 will move against the dog 81 but on such movements the dog will simply pass from 75 and return into the same recess 63, since at that time there is no movement of the plate 61 to carry the recess from the dog or to present a portion of its periphery to the dog. The dog 81 has a depending member 84, as 80 shown in Fig. 13, and this member is in the path of the cam-bar 83 and is acted upon thereby to displace the dog outwardly from the recesses of the plate 61. The dog 81 limits the advance movements of the rotary 85 frame 33 and prevents said frame from having reverse movements with the oscillatory plate 64.

A plate or shelf 99 may be secured to the far upper edge of the chute 30 and extend 90 in advance thereof to a sufficient extent to serve as a support for or to aid in supporting the plate 64 when the same is turned its full stroke by means of the handle 27, as 95 shown in Fig. 7.

Among the advantages of my invention I may call attention to the simplicity and durable nature of the mechanical parts of the machine, to the fact that during the operation of the machine the one handle 27, with 100 a coin in position, operates the plate 64 and rotates, by step-by-step movements always in the same direction, the rotary goods-holding frame 33 and plate 61, said frame 33 and plate 61 moving as one integral part, and to 105 the fact that the sold pieces of gum are not finally discharged under the pressure of any part acting against them but at a time when the plate 64 has returned to its normal position and the mechanism of the machine is at 110 rest, the sold piece merely falling by gravity when the support (plate 64) slides from below said piece, which is then stationary, and leaves its opening 68 between said piece and the open top of the chute 30. The machine 115 from which the drawings were made has a capacity for holding four hundred pieces of one cent gum. Other advantages of the invention will be apparent from the detailed description already given and it is believed further explanation is unnecessary.

What I claim as my invention and desire to secure by Letters-Patent, is—

1. A coin-controlled vending machine 120 comprising a base having a top plate, a vertical rotary frame having a series of vertical compartments or trays arranged to define a circular structure mounted over said top plate, and to receive stacks of the pieces 125 of goods to be sold, said top plate having a 130

hole therein over which said trays are successively moved and arrested and which hole is adapted to receive and confine one piece of the goods from the stack above it, a rotary plate below said top plate and connected with said rotary frame and having a series of recesses matching the trays of said rotary frame and to be successively moved below and arrested at said hole and said recesses upon aligning with said hole being adapted to receive therefrom the piece of goods previously confined in said hole, the stack then settling down to resupply a piece to said hole, an oscillatory plate close below and normally independent of said rotary plate and adapted to be keyed thereto by an introduced coin, said oscillatory plate having an exposed operating handle and serving as a support for the stack of goods above the hole in the top plate and the recess aligned therewith of said rotary plate and said oscillatory plate having an exit opening therein in advance of the hole in said top plate, said rotary plate when operated from the handle of said oscillatory plate being adapted to carry the piece of goods held in its recess forwardly below said top plate and to a location above the initial position of the exit opening in said oscillatory plate, and means for returning said oscillatory plate to its initial position, said oscillatory plate then carrying its exit opening below the said piece of goods moved by said rotary plate and permitting said piece to fall through said opening and pass to the purchaser.

2. A coin-controlled vending machine as claimed in claim 1, in which the oscillatory plate has a vertically disposed coin-receiver to snugly receive a coin on edge introduced through a vertical slot aligned therewith in said base, and in which said base is provided with a supporting tramway plate for the coin in said receiver, said tramway plate being so positioned with respect to said rotary plate as to maintain the upper face-edge of the coin in the adjacent recess of said rotary plate so that on the operation of said oscillatory plate the coin may engage the side edge of said recess and impart rotary motion to said rotary plate.

3. A coin-controlled vending machine as claimed in claim 1, having in said base a dog spring-pressed into one of the recesses in said rotary plate to prevent rotation of said plate except when the plate is keyed by a coin with said oscillatory plate, and also having a cam arm carried by said oscillatory plate to displace said dog from said recess and, when the rotary plate has been started in motion, to leave said dog to engage the periphery of said rotary plate and enter the succeeding recess thereof as said rotary plate is completing its predetermined movement.

4. A coin-controlled vending machine as claimed in claim 1, having in the side of said base a delivery opening for sold pieces of goods and having within the chamber of said base a chute leading to said opening and which chute has an open top close under said oscillatory plate and in register with the exit opening in said plate when the plate is in its initial position.

5. A coin-controlled vending machine as claimed in claim 1, having a glass casing mounted on said top plate and enclosing said rotary frame and having a central rod extending through said rotary frame and the bottom plate of said base and engaged with the top of said casing and the said bottom plate and detachably securing said casing and bottom plate in position.

6. A coin-controlled vending machine as claimed in claim 1, in which the top plate of the base has a central opening and the lower end of the rotary frame has a central hub mounted in said opening, and in which said rotary plate is secured to said hub and held close against the lower surface of said top plate.

7. A coin-controlled vending machine as claimed in claim 1, in which the inner faces of substantially opposite trays of the rotary frame are provided with ratchet teeth, and in which is provided a ring weight having inwardly extending arms conforming to said trays and resting upon the stacks of goods held by said trays, two of said arms having spring dogs to engage said teeth and while permitting the descent of the weight, preventing the weight from sliding from the goods should the machine be inverted or turned on its side, said dogs having finger-holds for their manual release from the ratchet teeth when the weight is to be slid upwardly.

8. A coin-controlled vending machine as claimed in claim 1, in which the rotary frame is formed of corresponding pieces of sheet metal forming the several trays and upper and lower collars or rings to which the trays are secured and which with the inner walls of the trays define an open center for the rotary frame, and in which said rotary frame is enclosed by an exterior casing mounted on the top plate of the base and detachably secured in position by a central vertical rod extending through said open center and connected with the top of said casing and the bottom of said base.

9. A coin-controlled vending machine comprising a base having a top-plate, a vertical rotary frame having a series of vertical compartments or trays arranged to define a circular structure mounted over said top plate and to receive stacks of the pieces of goods to be sold, said top plate having a hole therein over which said trays are successively moved and arrested and which

hole is adapted to receive and confine a piece of the goods falling from the stack arrested above it, a rotary plate below said top plate and secured to said rotary frame to rotate 5 the same and having a series of goods receiving recesses vertically aligned with the trays of said rotary frame and to be successively moved below and arrested at said hole as said trays are successively moved 10 over and arrested at said hole and said recesses upon aligning with said hole being adapted to receive therefrom the piece of goods previously confined in said hole, the stack then settling down to resupply a piece 15 to said hole, an oscillatory plate close below and normally independent of said rotary plate and adapted to be keyed thereto by an introduced coin, said oscillatory plate having an exposed operating handle and serving 20 as a support for the stack of goods in and above the hole in the top plate and the recess aligned therewith of said rotary plate, said rotary plate when operated from the handle of and while turning with said oscillatory plate being adapted to carry the 25 piece of goods held in its recess and sup-

ported upon said oscillatory plate forwardly below said top plate to a predetermined advance position, and means for returning said oscillatory plate to its initial position, 30 said oscillatory plate then sliding below said piece of goods held stationary in advance position in the recess of said rotary plate and leaving said piece unsupported so that the same may fall to the purchaser. 35

10. A coin-controlled vending machine as claimed in claim 9, having within said base an open-top chute below the said advance position for the piece of goods sold to receive said piece on the return to its initial 40 position of said oscillatory plate, and also having means for locking said rotary plate and said rotary frame on each of their step-by-step movements to respectively position a recess of the plate below and a tray of the 45 frame above the hole in said top plate, said base having a discharge opening to which said chute leads.

Signed at New York city, in the county of Kings and State of New York, this 26th day 50 of June A. D. 1923.

JENS N. MORTENSEN.
